UNITED STATES PATENT OFFICE.

GEORGE HENRY RUSSELL, OF FLORENCE, ALABAMA.

RAIL AND TIE TONGS.

1,286,789.

Specification of Letters Patent.

Patented Dec. 3, 1918.

Application filed October 17, 1918. Serial No. 258,501.

To all whom it may concern:

Be it known that I, GEORGE H. RUSSELL, a citizen of the United States, residing at Florence, in the county of Lauderdale and 5 State of Alabama, have invented a new and useful Rail and Tie Tongs, of which the following is a specification.

The subject of this invention is a rail and tie tongs, and the objects of the invention 10 are, first, to provide a unitary structure adapted for lifting both rails and ties, second, to provide a simple, durable and efficient rail and tie tongs.

With the foregoing and other objects in 15 view which will appear as the description proceeds, the invention resides in the combination and arrangement of parts and in the details of construction hereinafter described and claimed, it being understood that 20 changes in the precise embodiment of the invention herein disclosed, can be made within the scope of what is claimed, without departing from the spirit of the invention.

Figure 1 is a view in elevation of the tongs 25 as applied in lifting a rail.

Fig. 2 is a similar view showing the tongs applied to lifting a tie;

Fig. 3 is a top plan view of the tongs as viewed in Fig. 1.

30 Referring to the drawings by numerals of reference:

The tongs consist of two complementary bars 1—1 bent or looped at one end to form the handles 2. At their other ends these bars 35 1 merge into the curved or hooked gripping jaws 3 which are adapted to take under the ball of a rail 4, as seen most clearly in Fig.

1. At a median point on the curved or jaw portions 3, the bars are pivotally connected 40 by a pin or rivet 5.

Pivoted to each bar 1, near the pivotal

point of the bars, is a leg 6 formed with a toe 7. The toes 7, as will be seen, are opposed so as to form gripping elements. A connecting link 8 is bifurcated at each end to 45 straddle each leg 6 to a median point of which it is pivoted by a rivet 9.

When the tongs are in the position shown in Fig. 1 an upward movement of the handles 2 will cause the jaws 3 to be brought 50 together into gripping position.

With the tongs reversed, as seen in Fig. 2, upward movement of the handles 2 will force the toes 7 toward each other and cause them to grip the tie 10 while a contrary 55 motion of the handles will draw the toes apart and release the tie.

Having thus described the invention, what is claimed as new and sought by Letters Patent, is:—

1. A rail and tie tongs, comprising pivotally attached bars each bent at one end to form a handle and merging at the other end into a curved gripping jaw, a leg pivoted to each bar and extending in a direction opposite to the gripping jaw, and a link pivotally connecting the legs. 60

2. A rail and tie tongs, comprising pivotally attached bars each bent at one end to form a handle and merging at the other end 70 into a curved gripping jaw, a leg pivoted to each bar and extending in a direction opposite to the gripping jaw, and a link pivoted to a median point of each leg. 65

In testimony that I claim the foregoing 75 as my own, I have hereto affixed my signature in the presence of two witnesses.

GEORGE HENRY RUSSELL.

Witnesses:

J. I. MCCLURE,
D. O. WARREN.
